INVENTOR

Myron A. Gilman,

BY Webster & Co.,

ATTORNEYS.

UNITED STATES PATENT OFFICE.

MYRON A. GILMAN, OF WESTFIELD, MASSACHUSETTS.

DESIGN FOR A GARMENT-HANGER.

41,344.

Specification for Design.

Patented May 2, 1911.

Application filed February 18, 1910. Serial No. 544,716. Term of patent 7 years.

To all whom it may concern:

Be it known that I, MYRON A. GILMAN, a citizen of the United States of America, residing at Westfield, in the county of Hampden and State of Massachusetts, have invented a new, original, and ornamental Design for Garment-Hangers, of which the following is a specification, reference being had to the accompanying drawing, forming part thereof.

In the drawings, Figure 1 is an elevation of my design; Fig. 2, a perspective view of the same, and, Fig. 3, a plan view.

I claim:

The ornamental design for a garment hanger as shown.

MYRON A. GILMAN.

Witnesses:

F. A. CUTTER,
A. C. FAIRBANKS.
